JOHN F. METTEN, OF PHILADELPHIA, PENNSYLVANIA.

INTERNAL-COMBUSTION ENGINE.

Application filed June 9, 1922. Serial No. 567,026.

To all whom it may concern:

Be it known that I, JOHN F. METTEN, a citizen of the United States, residing at Philadelphia, in the county of Philadelphia and State of Pennsylvania, have invented 5 certain new and useful Improvements in Internal-Combustion Engines, of which the following is a specification.

This invention relates to internal combustion engines and particularly to such engines of the well known Diesel type. The object 10 of this invention is to provide an engine of this type which will be double-acting, developing driving pressure on each side of the piston. In the designs for double-acting oil engines proposed heretofore the conventional design of the single-acting engine has been generally followed by introducing a 15 stuffing box in a lower cylinder head which is fitted with the usual fuel, exhaust and intake valves. In other words, the design of the upper part of the single-acting cylinder has been applied to the space below the piston. This has necessarily resulted in extreme 20 difficulty in placing the lower group of valves owing to the space taken up at center by the water-cooled stuffing box around piston rod. In addition difficulty has been met in satisfactorily arranging for 25 the fuel injection owing to the interference of the piston rod. This has led to the employment of two piston rods, the fuel being injected across the lower combustion space 30 between the two rods. The group of valves installed in the lower or crank end of the cylinder result in such complicated arrangement of the valve gear as to render the stuffing boxes and the valves difficult of 35 access while the valve cages inserted from the bottom are difficult to handle. Another objection is that the jacket in a double-acting engine must carry off double the quantity of heat absorbed by the jacket than the single acting engine, while the cooling 40 area is only slightly increased by the surface of the lower head and the rod. In general the mechanical difficulties involved have proved such that the double acting engine of this type is still in an experimental stage.

50 In order to overcome these objections and provide a practical double acting Diesel engine the structure of this invention has cylinders arranged in pairs with one end of each cylinder of a pair in effective com-

munication with the opposite end of the 55 other cylinder and the pistons displaced 180° in the engine cycle. This permits the crank end of each cylinder to be free from valves so that the valves are in the upper part of the cylinders only. The combustion passages connecting the cylinders are also advantageous in operation and the structure as a whole provides an increased cooling 60 surface which avoids overheating of any of the engine parts.

65 In the accompanying drawings illustrating the invention—

Fig. 1 is a somewhat diagrammatic view 70 in vertical section of a pair of engine cylinders,

Fig. 2 is a similar section taken at right angles to the section of Fig. 1,

Fig. 3 is a horizontal section on line 3—3 of Fig. 1,

Fig. 4 is a vertical section on line 4—4 of 75 Fig. 3, and

Fig. 5 is a view similar to Fig. 4 illustrating a modification.

In the specific embodiment of the invention shown in the drawings a pair of cylinders 7, 8 having pistons 9 and 10 with piston rods 11 and 12 and connecting rods 13 and 14 drive the crank shaft 15. The crank bearings of the rods 13 and 14 are approximately 180° apart so piston 9 is moving up 80 while piston 10 is moving down and vice versa. The top of cylinder 7 is connected to the lower end of cylinder 8 by a passage 16 and similarly the top of cylinder 8 is 85 connected to the lower end of cylinder 7 by another passage 17. The passages 16 and 17 comprise cylindrical pipes extending between the cylinder castings and having bends at each end and the cylinders and pipes 16, 17 are all enclosed in a surrounding 90 casing 18 providing a water jacket around the cylinders and pipes, the water entering through supply pipes 19 and leaving through outlet pipe 20. Stuffing boxes 95 22 are provided in the lower cylinder heads while the upper cylinder heads have the usual intake and exhaust valves 23, 24 in the intake and exhaust passages 33, 34. Passages 16 and 17 are of such cross sectional 100 area as to provide proper velocities of intake air and exhaust to the space below the pistons and to give the requisite volumetric capacity for proper compression ratio.

Therefore each of these communicating passages becomes the combustion chamber into which fuel is injected and initial combustion takes place. The pistons 9, 10 have only sufficient clearance at the upper and lower edge at each end of their stroke to avoid the possibility of striking. Each pair of cylinders as shown on the drawings will then have two separate combustion chambers connecting the space below the piston in one cylinder to the space above the piston in the opposite cylinder. The fact that the force of combustion is from a common combustion chamber to the top of one piston acting on one crank and to the bottom of the other piston acting on the other crank insures an equal division of the load between the two cranks and these same conditions apply to the compression load and to the exhaust and intake strokes.

The combined passage and combustion chamber 16 or 17 is water jacketed all around and thus provides the necessary cooling capacity desirable in double acting engines of this Diesel type. While the water jacket system shown in the drawings is common to the two cylinders and the two combustion passages, separate jacket systems for the cylinders and combustion passages may be provided as desired for temperature control in practice. Since each combustion passage 16, 17 is of a length approximately equal to that of the cylinders ample axial space is provided for the spray from double fuel inlet 35 and there is ample travel of the oil particles in this space without striking cooled surfaces (see Fig. 4). The oil may be injected by air blast or the solid injection principle can be used. In the system shown in Figs. 1 to 4 fuel is admitted by a single fuel valve 35 located at the center of the combustion passage and arranged to discharge equal amounts of fuel in opposite directions parallel with the axis of the passage. Instead of this system two separate fuel valves 36, 37 may be used (see Fig. 5) one located at each end of the combustion passage. Owing to the length of travel of the fuel particles permissible with such a form of combustion chamber a spray of high velocity can be employed of such form as to facilitate a high degree of atomization combined with a maximum penetration of the compressed charge of air. The delivery of the compressed charge simultaneously to opposite ends of the combustion passage causes an increased turbulence of the charge and a correspondingly improved combustion.

In the specific example shown in the drawings the engine is of the four cycle type, the details of the usual valve gearing being omitted for the sake of simplicity. In each cylinder the intake valve 23 opens during a downward stroke of its piston and admits a charge of air to the upper end of its

cylinder and through this cylinder and the connecting combustion passage to the lower end of the other cylinder. The succeeding upward stroke of the one piston and the corresponding downward stroke of the other further compress the air and, as the pistons reach the end of the compression stroke, the fuel is injected through the fuel valve or valves and thoroughly mixes and combines with the air in the connecting combustion passage. The combustion of the atomized fuel and the resulting expansion drives one piston down and the other up and the exhaust gases on the next stroke pass out through the combustion passage and exhaust valve.

It is well known that the maximum temperatures exist in the initial combustion space, which in the present standard form of single or double-acting internal combustion engine is in the shape of a shallow disc, the periphery of which is formed by the cylinder bore and the upper and lower surfaces by the inner cylinder head and piston walls. These walls involve, by reason of their relatively large unsupported area, thicknesses of metal that are greater than desirable for maintaining the proper temperature gradient in the wall, being exposed on one side to the intense heat of combustion under high pressure and on the other to the temperature of the comparatively cool circulating water. The restricted travel necessarily involved before the entering fuel impinges on the metal surfaces results in a high local concentration of the heat, particularly on the piston head. By the combustion passage 16, 17 of this invention a chamber is provided which is common to the working ends of adjacent cylinders and the initial combustion is confined to this chamber which is of such form as to give maximum resistance to internal pressure for a given wall thickness. With this arrangement the high initial temperatures surrounding the point of admission of fuel are not directed upon the horizontal piston or cylinder head walls but are concentrated in a chamber with vertical surfaces of moderate thickness that can be more effectively cooled, and by reason of its form it is free from features that are likely to result in cracks forming from overheating. Advantage can therefore be taken of higher compression ratios and initial pressures.

The principle of this invention may be extended to multi-cylinder engines having a larger number of cylinders by arranging the cylinders in groups up to any number required. While the invention is illustrated in connection with specific embodiment in a four cycle engine it is not confined thereto but may be used in two cycle engines. The valves also may be variously placed as desired for instance to position the intake and

exhaust valves nearer to or within the combustion passages and to change the location of the fuel valve to give the most advantageous distribution of the fuel in the combustion spaces.

5 I claim:—

1. In an oil engine, the combination with the engine cylinder, of a combustion chamber extending lengthwise at the side of said cylinder, intake and exhaust valves, and means for injecting fuel oil in said chamber in opposite directions.

2. In an internal combustion engine the combination with a cylinder and valves 15 therefor of a combustion chamber of generally cylindrical form connected to the end of said cylinder, and a fuel supplying means in said chamber adapted to inject fuel in a direction parallel to said cylinder.

20 3. In an oil engine, the combination with a plurality of engine cylinders, of a combustion chamber connecting the outer end of one cylinder with the inner end of another cylinder, intake and exhaust valves located at the outer end of one of the cylinders, and means for injecting fuel oil in said chamber.

25 4. In an oil engine, the combination with a plurality of engine cylinders, of a combustion chamber connecting the outer end of one cylinder with the inner end of another cylinder, intake and exhaust valves located at the outer end of one of the cylinders, and means for injecting fuel oil in 35 said chamber in opposite directions.

5. In an oil engine, the combination with a plurality of engine cylinders, of a combustion chamber extending lengthwise with relation to said cylinders and connecting the 40 end of one cylinder with the end of another cylinder, intake and exhaust valves, and means for injecting fuel oil in said chamber in the direction of length of said chamber.

45 6. In an internal combustion engine the combination with a plurality of cylinders, of a combustion chamber connecting the end of one cylinder to the opposite end of another cylinder, and a fuel supply means in said passage adapted to inject fuel in opposite directions along the length of said passage.

50 7. In an oil engine, the combination with a plurality of engine cylinders, of a combustion chamber connecting the outer end of one cylinder with the inner end of another cylinder, a second combustion chamber connecting the outer end of the second cylinder with the inner end of another cylinder, intake and exhaust valves, and means for in-

jecting fuel oil in said chambers in opposite directions.

8. In an oil engine, the combination with a plurality of engine cylinders, of a combustion chamber connecting the outer end 65 of one cylinder with the inner end of another cylinder, a second combustion chamber connecting the outer end of the second cylinder with the inner end of another cylinder, said combustion chambers extending 70 lengthwise with relation to said cylinders, intake and exhaust valves, and means for injecting fuel oil in said chambers in the direction of length of said chambers.

9. In an oil engine, the combination with a 75 plurality of engine cylinders, of a combustion chamber connecting the outer end of one cylinder with the inner end of another cylinder, a second combustion chamber connecting the outer end of the second cylinder 80 with the inner end of another cylinder, intake and exhaust valves located at the outer ends of the cylinders, and means for injecting fuel oil in said chambers.

10. In an internal combustion engine, a 85 pair of engine cylinders, a pair of passages extending parallel to said cylinders, one of said passages being connected with the outer end of one of said cylinders and with the inner end of the other of said cylinders, and 90 the other of said passages being connected with the inner end of the first cylinder and the outer end of the other cylinder, and intake and exhaust valves on the outer ends of said cylinders to cause said passages to act 95 as intake and exhaust passages to the inner ends of said cylinders.

11. In a double acting oil engine, a pair of engine cylinders, a pair of combustion chambers extending parallel to said cylinders, one 100 of said chambers being connected with the outer end of one of said cylinders and the inner end of the other of said cylinders, and the other of said chambers being connected with the inner end of the first cylinder and the 105 other end of the second cylinder, intake and exhaust valves on the outer ends of said cylinders to cause said chamber to act as intake and exhaust passages to the inner ends of said cylinders, and means for injecting fuel 110 oil in said chambers in opposite directions along the length of said chambers.

12. A double acting internal combustion engine comprising a pair of cylinders having their opposite ends connected by combustion passages extending parallel to said cylinders and having fuel supply means adapted to inject fuel in opposite directions along the length of said passages.

JOHN F. METTEN.
